UNITED STATES PATENT OFFICE.

HENRY PETERSEN, OF MOUNT AUBURN, IOWA.

DRAFT-EQUALIZER.

1,099,204.

Specification of Letters Patent.

Patented June 9, 1914.

Application filed February 18, 1914. Serial No. 819,427.

To all whom it may concern:

Be it known that I, HENRY PETERSEN, a citizen of the United States of America, and resident of Mount Auburn, in the county of 5 Benton and State of Iowa, have invented certain new and useful Improvements in Draft-Equalizers, of which the following is a specification.

This invention relates to certain new and 10 useful improvements in draft equalizers and it has for its objects among others to provide a construction whereby I can obtain the maximum amount of movement of the doubletree or evener bar for the hitch of the 15 draft animal, and to apply all of the draft strain to the depending oscillating bars and then divide such strain between the main frame and the gang frame. I connect the 20 doubletree or evener bar with the oscillating bars independently of each other for independent movement of the gangs, and in some instances provide a carrier and guide support for the doubletree or evener bar, and mount the same so as to minimize the friction. 25 I provide for the lateral adjustment of the oscillating bars to control the crowding in or out of the gangs. By applying the draft strain partly on the main frame and partly on the gang frame, I am enabled to hold 30 the earth-engaging members down steady against their work. The depending bars are mounted to oscillate independently of each other in the direction of the draft strain to the extent of the movement of the gang 35 frame in the line of draft.

Other objects and advantages of the invention will hereinafter appear and the novel features thereof will be particularly pointed out in the appended claims.

40 The invention is clearly illustrated in the accompanying drawings, which, with the numerals of reference marked thereon, form a part of this specification, and in which—

45 Figure 1 is an elevation showing the application of my present invention to one form of cultivator. Fig. 2 is a perspective view of the parts embodying my present invention. Fig. 3 is a fragmentary view with portions broken away and parts in section 50 through the pivot of the doubletree or evener bar. Fig. 4 is a perspective detail of a portion of one form of yoke. Fig. 5 is a perspective view showing a slightly modified form. Fig. 6 is a perspective detail showing a modified form of yoke with oscillating-

bar adjusting-means. Fig. 7 is an enlarged detail in elevation with the tongue in section showing the form of adjusting means illustrated in Fig. 6.

Like numerals of reference indicate like 60 parts throughout the different views.

Referring to the drawings, 1, 1 are depending bars or members mounted for independent oscillatory movement upon some fixed part of the cultivator or other implement or vehicle, either the frame or tongue, in the present instance being shown as mounted upon the tongue 2. These oscillatory bars may be mounted in a variety of ways, in the present instance being shown as 70 mounted upon the pivot rod 3 held in a casting or the like 4 fixedly secured to the tongue. Any other convenient form of mounting, however, may be employed. The lower ends of these oscillating bars are provided with openings or the like 5 for the attachment of chains or other ligaments 6, the other ends of the which are connected with the gang frame 7. The form of ligament and the manner of connection is im- 75 material. The ligaments are, in practice, such as to permit of adjustment thereof so as to vary the distance between the lower ends of the oscillating bars and their point of connection with the gang frame. This 80 may be readily done by changing the links of a chain or the adjustment of a strap or bar in any well known way.

The gang frame and other portions of the cultivator may be of any of the well known 85 or approved forms of construction, that herein shown being merely for the purpose of illustration to show the application of my present improvements. A detailed description, therefore, of these parts is not deemed 90 necessary further than to state that 8, 8 are side bars of the frame, 9 the mast, 10 the pendulum bar, 11 the lifting bar and 12 the lever employed for raising and lowering the 95 gangs. In Fig. 1 the full lines represent the position of the parts when the gangs are 100 down in operative position. The dotted lines indicate the position of the parts when the gang frame is raised and the earth-engaging implements out of operative position. 105

My present improvement is capable of embodiment in a variety of forms, some only of which are herein illustrated, and upon reference first to Figs. 2, 3 and 4 there will be seen a yoke, the side bars 13 of which 110

are pivotally connected, as at 14, with the depending oscillatory bars 1 at a point at or above the center of said depending bars, suitable means, such as the plurality of holes 15 in the bars 1, being provided for vertical adjustment of the connection of the side bars 13 and depending bars 1 to vary the draft on the gang frame, it being understood that as more draft is put upon the gang frame the draft on the tongue or main frame is correspondingly decreased, and vice versa. The cross bar 16 of this yoke is pivotally mounted, at its ends, as at 17, to the ends of the side bars 13, so as to equalize the force or draft strain on the depending oscillatory bars 1.

18 is the doubletree or evener bar provided at its ends with the holes 19 for the attachment of the swingletrees for the attachment of the draft animals. This doubletree or evener bar is pivotally mounted between its ends for freedom of movement independent of the yoke, the manner of pivoting being immaterial, and above this doubletree or evener bar is a casting or carrier or frame 20 embracing in this instance the tongue 2 so as to steady the doubletree and this carrier 20 is provided with rollers 21 mounted for engagement with the upper face of the tongue, an additional roller or rollers being provided beneath the casting for engagement with the under side of the tongue, if desired.

In some instances I may deem it advisable to employ a washer as 22 in Fig. 2, which may be applied about the pivot 23 of the doubletree or evener bar 18 and which washer may be either above or below said doubletree, or I may sometimes employ one above and one below said doubletree.

The cross bar 16 of the yoke may in some instances be provided with an upwardly extending teat 24, as seen in Fig. 3, which is received in an opening in the doubletree 18 and which, in turn, receives the pivot bolt 23.

With the parts constructed and arranged substantially as hereinbefore described, the operation, briefly stated, is as follows: The draft being applied to the ends of the doubletree or evener bar 18 in the usual way, the oscillating bars 1, 1 serve as evener bars and the draft strain is divided between the main frame and the gang frame, being more or less upon the gang frame according to whether the pivots 14 of the side bars 13 of the yoke are adjusted farther downward or upward. The draft strain being applied partly on the main frame and partly on the gang frame serves to hold the earth-engaging implements down steady against their work. By reason of the depending bars 1 being capable of oscillatory movement independently of each other in the direction of the draft strain

and also independent of the equalizing bar 16 and the doubletree or evener bar 18, the strain from the doubletree 18 is equally sustained by the oscillating bars 1, 1. By the employment of the doubletree 18, maximum movement of the draft animals is permitted, so that unequal pulling by the draft animals at a long varying distance does not put more strain upon one than the other and the two depending oscillatory bars 1, 1 each sustains the same amount of strain or pressure under all conditions.

It is to be noted that the draft strain is not applied directly to the oscillating bars, as has heretofore been done using a main doubletree, but the draft animals are attached directly to the ends of the main doubletree.

In Fig. 6 I have shown a construction, the operation of which is substantially the same as that hereinbefore described in connection with Fig. 2 except that the yoke is rigid, that is in one piece. This yoke has its side bars 25 pivotally connected, as at 26, with the oscillating bars 1, 1, the cross portion 27 of said yoke being provided with an upwardly extending teat 28 similar to the teat 23 in the form shown in Fig. 3 and for a like purpose.

In Fig. 5 I have shown a carrier 29 provided with a single roller 30 bearing on the upper face of the tongue. In order to provide for the lateral adjustment of the oscillating bars 1 to control the crowding in or out of the gangs, various means may be employed. In Fig. 5 I have shown the form of yoke illustrated in Figs. 2 and 4 and I connect the oscillating bars 1, 1, preferably at their points of connection with the side bars 13 of the yoke, with the side bars 8 of the frame. In this form I show rods 31 and 32 connected by a turn buckle 33 by adjustment of which in a well known way, the oscillating bars 1, 1 are spread farther apart or drawn nearer to each other, so as to bring the oscillating bars in line with the coupling beam of the gang frame to control the crowding in or out of the gangs. It is to be noted that the depending bars 1, 1 are adjustable each independently of the other, so that the oscillating bars may be adjusted more or less as necessity may require. It will be understood that if the gang frame is crowding out, the oscillating bar is adjusted inward to compensate therefor, and vice versa.

In Figs. 6 and 7 I have shown another form of means for the in and out adjustment of the depending bars 1, 1, in connection with the rigid yoke hereinbefore described. In this form the bars 1, 1 are independently adjustable in or out for the purpose hereinbefore described by means of the wheels or thumb nuts 34 and 35 on the pivots of said bars 1, 1 and operating in a well known way.

The side bars 25, 25 of the yoke are sufficiently rigid to sustain the bars 1, 1 in their adjusted position without the employment of the transverse rods, such as seen in the form 5 illustrated in Fig. 5.

While in the present instance I have shown my improvements with the parts so disposed that the doubletree or evener bar 18 is to the rear of the depending oscillating bars 1, it is evident that the position of the parts may be reversed, that is, turned end for end so that the doubletree or evener bar 18 will be in front and the depending bars 1 to the rear. In this reversed position 15 the operation is practically the same and a like result attained.

Modifications in detail, proportion of parts etc. may be resorted to without departing from the spirit of the invention or 20 sacrificing any of its advantages.

What is claimed as new is:—

1. In a draft equalizer, an evener bar, depending oscillatory bars, a horizontal yoke connection between the same and the evener 25 bar, and means for applying the draft directly to the evener bar.

2. In a draft equalizer, a slidably and pivotally mounted evener bar, depending bars mounted for independent oscillatory movement, and means connecting the oscillatory 30 bars and the evener bar and movable with the latter, and means for applying the draft directly to the evener bar.

3. In a draft equalizer, a pivotally mounted doubletree, depending bars mounted for independent oscillatory movement, a yoke pivotally connected with said bars, and means connecting said yoke and doubletree to allow the doubletree to move independently of the yoke and also therewith.

4. In a draft equalizer, a pivotally mounted doubletree, depending bars mounted for independent oscillatory movement, a yoke pivotally connected with said bars, and means for adjusting the connection between said yoke and bars.

5. In a draft equalizer, a pivotally mounted doubletree, oscillatory bars, a yoke pivotally connected with said bars and movable 50 with or independent of the doubletree, and

means for adjusting the connection between said yoke and bars.

6. In a draft equalizer, a pivotally mounted doubletree, depending oscillatory bars, means connecting said bars and doubletree, 55 to allow of independent or unitary movement, and means for adjusting said bars to and from each other.

7. In a draft equalizer, a pivotally mounted doubletree, depending oscillatory bars, 60 means connecting said bars and doubletree to allow of independent or unitary movement, means for adjusting said bars to and from each other, and means for adjusting the pivotal connection between said bars and doubletree.

8. In a draft equalizer, a pivotally mounted doubletree, depending oscillatory bars, a yoke pivotally connected with said bars, a pivot common to said yoke and doubletree, 70 and means for applying the draft directly to the doubletree.

9. In a draft equalizer, a pivotally mounted doubletree, depending oscillatory bars, a yoke pivotally connected with said bars, a 75 pivot common to said yoke and doubletree, means for applying the draft directly to the doubletree, and means for adjusting the bars laterally to and from each other.

10. In a draft equalizer, a pivotally mounted doubletree, depending oscillatory bars, a yoke pivotally connected with said bars, a pivot common to said yoke and doubletree, means for applying the draft directly to the doubletree, and an anti-friction 85 device movable with the doubletree.

11. In a draft equalizer, a pivotally mounted doubletree, means for applying all of the animal draft directly to said doubletree, and means for dividing the draft strain 90 between the main frame and the gangs, thereby lessening the strain on the machine and the operator.

Signed by me at Washington, D. C., this 18th day of February, 1914.

HENRY PETERSEN.
